O. A. MILLER.
WHEEL DRESSING TOOL.
APPLICATION FILED MAY 3, 1919.

1,387,427.

Patented Aug. 9, 1921.

Inventor

UNITED STATES PATENT OFFICE.

OTTO A. MILLER, OF DETROIT, MICHIGAN.

WHEEL-DRESSING TOOL.

1,387,427.

Specification of Letters Patent. Patented Aug. 9, 1921.

Application filed May 3, 1919. Serial No. 294,462.

To all whom it may concern:

Be it known that I, OTTO A. MILLER, a citizen of the United States of America, residing at Detroit, in the county of Wayne and State of Michigan, have invented certain new and useful Improvements in Wheel-Dressing Tools, of which the following is a specification, reference being had therein to the accompanying drawings.

10 The primary object of my invention is to provide a novel wheel dressing tool that may be advantageously used for dressing the periphery of an emery wheel, grinding or finishing wheel, so that the wheel will have a 15 concave or convex periphery of desired conformation for grinding or finishing pieces of work.

Another object of my invention is to provide a tool of the above class where positive 20 and reliable means are employed in a manner as hereinafter set forth for adjustably supporting a diamond mounting or other wheel dressing instrumentality so that the diamond mounting may be fed into engagement 25 with the periphery of the wheel for cutting or dressing a convex surface thereon or a concave groove therein, and provision is made whereby the adjustment may be predetermined and ascertained from time to 30 time for a proper degree of dressing.

A further object of my invention is to provide a wheel dressing tool of the above class wherein the parts are constructed with a view of reducing the cost of manufacture 35 and at the same time retain those features by which safety, durability and ease of assembling are secured. With such ends in view, my invention resides in the novel construction to be hereinafter considered and then 40 claimed.

Reference will now be had to the drawings wherein,

Figure 1 is a plan of the wheel dressing tool;

45 Fig. 2 is a longitudinal sectional view taken on the line II—II of Fig. 1;

Fig. 3 is a cross sectional view taken on the line III—III of Fig. 1, and

50 Fig. 4 is an end view of a portion of the tool, partly broken away and partly in section.

In the drawing, the reference numeral 1, denotes a base, which in plan has its front portion or edge semi-circular and its rear

portion or edge rectangular or square. The 55 sides of the base have slotted ears 2 so that it may be conveniently secured on a machine body or adjacent an emery or other grinding wheel. To further facilitate placing the base 1 relative to various types of grinding 60 wheels, the rear portion of said base has posts 3 vertically disposed within the base and slidably retained therein by pins 4. The 65 posts 3 are frictionally held in adjusted position by set screws 5 engaging pieces of rubber 6 in the base 1 against said posts, and the pieces of rubber 6 may be compressed by the set screws 5 to hold the posts raised in inactive positions or lowered in active positions, as occasion may require.

70 Rotatable on the base 1 and retained in engagement therewith by a central screw 7 or other pivotal means is a guide member 8 having a rearward extension 9 which together with said guide supports a dovetailed 75 tongue 10 having a longitudinal groove 11 in the greater part thereof. The rotary guide member 8 may be swung about the axis of the screw or pivot 7 and the upper face of the base 1 is graduated or calibrated, 80 as at 12, so that the rotary guide member may be swung in an arc of a desired number of degrees. As shown in Fig. 1, the base 1 has four sets of graduations or calibrations and the rotary guide member 8 provided 85 with suitable indicators whereby the operator of the tool may accurately move the rotary guide member a desired number of degrees.

Slidably longitudinally of the tongue 10 is 90 a conical support 13 having a depending nut 14 extending into the groove 11 of the tongue 10. In screwthreaded engagement with the nut 14 is a screw 15 within the groove 11, and said screw is part of a handle 16 journaled in the rearward extension 9 of the rotary guide member 8. The manner of rotatably holding the handle 16 and the screw 15 in engagement with the rotary guide member is clearly shown in Fig. 2, 100 and it is only necessary to rotate the handle 16 to impart a reciprocatory movement to the conical support 13 on the tongue 10 of the rotary guide member.

105 Detachably connected to the conical support 13 is a vertically disposed holder 17 for a laterally disposed diamond mounting 18. The holder 17 is set in the axis of the sup-

port 13 and said holder has a radially disposed pin 19 adapted to extend into either of the slots 20 provided therefor in the upper end of the support 13, said slots being disposed ninety degrees apart so that the holder may be positioned to present the diamond mounting 18 at either side or the front of the tool. To lock the holder 17 against accidental displacement, the support 13 has a set screw 21 in the rear side thereof adapted to be adjusted to bind the holder in said support.

The upper end of the holder 17 is bifurcated and formed with sockets 22, either of which may accommodate the diamond mounting 18, said diamond mounting being clamped in its socket by a screw 23 transversely of the upper end of the holder 17, said screw contracting the bifurcated end of the holder about the diamond mounting so that it cannot become accidentally displaced. When the uppermost socket 22 is used for the diamond mounting 18, the upper end of the holder may have a set screw 24 to engage the diamond mounting and further hold said mounting against displacement.

Longitudinal movement of the conical support 13 on the tongue 10, may be prevented by a set screw 25 carried by the support 13, said set screw engaging a pin 26 in the support that is adapted to bind against the tongue 10 and prevent longitudinal movement of said support.

Rotary movement of the guide member 8 on the base 1 may be prevented by a set screw 27 carried by the base 1, said set screw engaging the screw or pivot 7 of the rotary guide member 8 so as to hold said screw and pivot stationary.

Fixed on the rearward extension 9 of the rotary guide member 8 is a vertically disposed gage 28 that may be fixed to the rearward extension 9 by screws 29 or other fastening means. The gage 28 is of a height corresponding to the holder 17 and permits of a pair of calipers, a micrometer or other instrument being positioned, with the diamond mounting 18 and the gage 28 as terminals, for determining the distance the holder 17 has been moved to and from the gage 28. Since the gage 28 has a fixed and known relation to the axis of the tool it is easy to determine the movement of the diamond mounting at either side of the tool axis.

To place the tool in operation, the base 1 is positioned adjacent an emery or grinding wheel so that the axis of the holder 17 will be at a tangent to the periphery of the emery wheel. Then by advancing the holder 17 toward the wheel and oscillating the handle 16 the periphery of the wheel may be provided with a groove of desired contour. By moving the holder 17 away from the periphery of the wheel and oscillating the

handle 16 the periphery of the wheel may be provided with a convex surface of desired contour, the contour in either instance being determined by measurements between the diamond mounting 18 and the gage 28, also by the degree of oscillation imparted to the handle 16.

The novel adjustments of the tool permit of the periphery of a wheel being attacked from a desired angle so that most any desired contour may be imparted to the periphery of the wheel, and while in the drawing there is illustrated a preferred embodiment of my invention, it is to be understood that the structural elements are susceptible to such change in size, shape and manner of assemblage, as fall within the scope of the appended claims.

What I claim is:—

1. A wheel dressing tool comprising a base, a rotatable guide member on said base and provided with a tongue, an adjustable support having connection with the tongue of said guide member, an adjustable holder carried by said support, a diamond mounting carried by said holder, a nut and screw adapted for adjusting said support relative to the tongue of said rotary guide member, and a gage carried by said rotatable guide member and disposed in parallelism with said holder.

2. A wheel dressing tool comprising a base, a rotatable guide member pivoted on said base, means for fixing said rotatable guide member relative to said base, an adjustable support on said rotatable guide member, means adapted for fixing said support relative to said rotatable guide member, a vertically disposed diamond mounting holder supported from said support in the axis thereof, and means extending in said rotatable guide member and engaging the lower end of said diamond mounting holder adapted for simultaneously moving said rotatable guide member relative to said base, and said support and its holder relative to said rotatable guide member.

3. A wheel dressing tool as characterized in claim 2 wherein the rotatable guide member is provided with a gage disposed parallel to the axis of said support.

4. A wheel dressing tool comprising a base, a rotatable guide member on said base, a tongue on said guide member provided with a groove, an adjustable support having a groove to receive the tongue of said guide member, an adjustable vertical holder carried by said support in the axis thereof and having its lower end extending into the groove of said tongue, means carried by said holder and engaging in said support, so that said holder may have a defined position relative to said support, a diamond mounting carried by said holder, and a screw in the groove of said tongue engaging the lower end of said

holder adapted for adjusting said support and holder relative to the tongue of said rotary guide member.

5. A wheel dressing tool as characterized in claim 4 wherein the rotatable guide member is provided with a gage disposed in parallelism with said holder.

In testimony whereof I affix my signature in the presence of two witnesses.

OTTO A. MILLER.
